(57) CLAIM

The ornamental design for a bra, as shown and described.

DESCRIPTION

FIG. 1 is a perspective view of a bra showing my claimed design shown in an environment of use, on a person;

FIG. 2 is a front view of the bra of FIG. 1;

FIG. 3 is a back view of the bra of FIG. 1;

FIG. 4 is a left side view of the bra of FIG. 1;

FIG. 5 is a right side view of the bra of FIG. 1;

FIG. 6 is a top view of the bra of FIG. 1; and,

FIG. 7 is a bottom view of the bra of FIG. 1.

The broken lines in FIG. 1 showing a person are for the purpose of illustrating environmental structure and form no part of the claimed design. The person in FIG. 1 is shown with symbolic breaks on two sides. The appearance of any portion of the person between the break lines forms no part of the claimed design. In addition, the broken lines in FIGS. 1-7 showing an ornament between the two bra cups and a pair of nursing clips form no part of the claimed design. The dashed lines in FIGS. 1-7 depict stitching, which do form part of the claimed design.
